Patented Oct. 31, 1832.

Francis Shumard of Cincinnati, Ohio
Sellers Patent.

The Vegetable referred to in these Letters Patent and making part of the same containing a description in the words of the said Francis Shumard himself of his Improvement in the Saw-mill by which Laths are cut with circular saws.

To all whom it may concern. Be it known that Francis Shumard of Cincinnati in the County of Hamilton and State of Ohio have invented an improvement in the saw-mill, by the application of which circular saws are made to cut laths or other light work on the edge and the side at one operation and that the following is a full and exact description of the said machinery as invented by me. The log to be sawed into laths or other strips is first cut to the required length, and then fixed upon a saw carriage with suitable head blocks. This carriage may be made to traverse back and forward by means of any appropriate gearing. That which I commonly use, and which I prefer to any other, is the crank motion communicated from a revolving shaft by means of a pitman. The two shafts of the circular saws run in a frame which is made to slide up and down between vertical chutes above the log by means of a lever a rack and pinion or other contrivance. The frame may be raised or lowered so as to adapt the saws to the dimensions of the log. I usually employ one saw running horizontally and two or more running vertically which latter cut the laths or other strips to a proper thickness, whilst the former cuts them off at their ends.

The saws are made to cut as the log passes in either direction thereby saving the time which would otherwise be expended in drawing the log back. For the purpose of setting or of moving the log sideways the carriage is divided into two parts one of which runs upon suitable rails on the other. An iron shaft under the upper section of the carriage is attached to the side of a log which passes through the frame, and is held with pitch and noted... only a few hands on the man driving the log sideways to such a distance as shall correspond

with the thickness to be cut. At each end of the frame on which the carriage moves there are attached blocks or stoppers against which it is to run, so as to give revolution of the crank, the hand, stirrup and counterpoise so as to act upon the rag wheel in the opposite degree.

By means of the drawings deposited in the Patent Office and their names there to annex, the various parts which I have described and their mode of action will be readily understood.

What I claim as my invention and for which I ask a patent is the carriage, ^{the} way to act as the log travesy in either direction, the mode of moving the log sideways as above described, the combined use of the vertical and horizontal ways, cutting the sides and edges of the latter, simultaneously, the mode of adjusting the ways, by means of the sliding frame and the general construction and arrangement of the apparatus by which the intended effect is produced.
